ELECTRIC CIRCUIT BREAKER WITH COM-
PRESSED FLUID BLOWOUTBernard Marie Hilaire Paul Fernier, Lyon,
France; vested in the Alien Property Custo-
dianApplication July 29, 1939, Serial No. 287,348
In Germany July 30, 1938

5 Claims. (Cl. 200—148)

This invention relates to electric circuit-breakers and more particularly to those which themselves supply the energy required for blowing the arc.

Circuit-breakers which themselves supply the energy required for blowing the arc generally comprise means for storing up potential energy during the operation of closing the contacts and then deliver said energy on separation of the contacts to impart to the fluid for blowing the arc a certain degree of pressure. Compressed air is generally used to blow the arc. The potential energy referred to is predetermined for a given type of apparatus. When the intensities of the short circuit currents to be broken exceed a certain value, the type of circuit-breaker referred to can no longer be used, as it then becomes necessary to supply supplementary energy from a source outside or apart from the circuit-breaker.

One of the objects of the present invention is to provide an electric circuit-breaker with compressed fluid blow out and which supplies its own energy for blowing the arc, in which the rupturing power is increased. With this object in view the circuit-breaker in accordance with the invention contemplates the production by said circuit-breaker of a supplementary quantity of energy over and above a given intensity of current which passes through the arc at break, said supplementary quantity of energy being supplied from a different source from the latter for effecting the blow out.

In accordance with the invention the two quantities of energy referred to may act simultaneously or else said supplementary energy acts first and produces a preponderating blast, the blast produced by the other quantity of energy not beginning to act until some time after said former quantity.

The invention has other aims and objects in addition to those above set forth, all of which will be readily understood from the following description taken in connection with the accompanying drawings of embodiments of the invention herein given for illustrative purposes, the true scope of the invention being more particularly pointed out in the appended claims.

Fig. 1 shows an illustrative embodiment of the invention;

Fig. 2 is a longitudinal section of that part of the circuit-breaker containing the fixed contact and the two auxiliary contacts, and illustrates, upon a larger scale, the means for obtaining a concentric flow of the air currents;

Fig. 3 illustrates certain modifications of the apparatus shown in Fig. 1;

Fig. 4 shows further modifications;

Figs. 5, 6, 7 show the cam 3 in three principal positions.

Referring to Fig. 1 there is therein represented partly in elevation and section and partly in perspective a circuit-breaker of the general type described comprising an air compressor having a piston operated by a spring and tensioned before the closing of the contacts of said circuit-breaker, said spring being capable of storing up in advance the energy required for the closing and separating of said contacts as well as the energy required to produce the compressed air required for blowing the arc.

In said figure the compressor piston 1 is connected on the one hand to the free end of a powerful spring 2 and on the other hand to a cam

20 3 which is operated by mechanism herein shown in perspective for the sake of clearness. A shaft 4 of this mechanism is directed perpendicularly to the plane of said figure and its projection is shown at 4' which designates the axis of oscillation of the cam, which is moved by said mechanism in a contra-clockwise direction. In the course of this rotary movement it can engage and carry with it a roller 5 upon one arm of a bell crank lever 6 which controls the main movable

25 contact 7 of the circuit-breaker, the fixed contact of which is indicated by 8. These two contacts draw an arc herein called the principal arc and designated by 9. Said circuit-breaker is further provided with an auxiliary fixed contact 10 and an auxiliary movable contact 11 which, when the intensity of the current to be broken exceeds a given value, draw an arc herein called the auxiliary arc and designated by 12 and which is struck in series with the main arc (or principal arc).

30 In this figure the circuit-breaker is shown with its arc drawing contacts separated, the action of the cam 3 on the movable contact 7 then being as follows. Said cam has a full portion 3a and a cam groove 3b. When said cam engages said roller 5 said full portion 3a causes the lever 6 to swing clockwise about its fulcrum thus closing said principal contacts 7 and 8. With the circuit-breaker being thus in circuit closing position, said

35 45 50 55 roller 5 is opposite the entrance of said cam groove 3b. The separation of said two principal contacts takes place by a further rotation of said cam 3 in the course of which said roller 5 leaves said cam groove 3b. The details of this operation will appear more fully below. The auxiliary

movable contact 11 is operated by a bell crank lever 13 against the action of a spring 14 which tends to keep the auxiliary contacts 10 and 11 separated. These two contacts are kept in closed position by a bell crank lever 15, one arm of which is opposite the movable core of an electric relay 16 which is energized by the main current passing through the circuit-breaker.

The tensioning of spring 2 to store up energy to close and then to separate the contacts of the circuit-breaker and to blow the principal arc, is effected as follows:

Rotation of the shaft 4 on which is splined the cam 3 is effected by a crank 17 which by means of an endless screw device 18 of which the wheel is loose upon said shaft, and a lever 19 actuates a driving member 20 carried by said shaft. When in its contra-clockwise rotation said cam brings its end 3a opposite said roller 5, said spring 2 will be tensioned and a pawl 21 engages a bell crank lever 22 of which one arm is opposite the movable core of a winding 23 adapted to effect closing movement of the contacts of the circuit-breaker. Furthermore, by the tensioning movement of said spring 2 an inclined plane 24 is moved to act upon a roller 25 carried by a bell crank lever 26 and thus through a suitable connection swinging said bell crank lever 13 contra-clockwise about a fulcrum to close the auxiliary contacts 10, 11, said lever 13 engaging said bell crank lever 15.

Closing movement of the principal contacts 7 and 8 of the circuit-breaker is effected by sending an energizing current through the winding 23 which causes the movable core of the latter to swing the bell crank lever 22 about its fulcrum thus freeing the pawl 21. Said shaft 4 is thus unlocked, and under the action of said spring 2, said cam 3 is rotated counter clockwise and rotates said shaft 4. During this time the part 3a of said cam 3 causes bell crank lever 6 to swing clockwise about its fulcrum to close the principal contacts 7 and 8. When said contacts are thus closed, pawl 21 engages bell crank lever 21, one arm of which is opposite the movable core of a winding or coil 23 adapted to effect the separation of said principal contact.

To effect an ordinary separation of said contacts an energizing current is sent through said coil 28. The resulting movement of its coil rotates said lever 27 and disengages said pawl 21. Shaft 4 being thus unlocked, cam 3 is caused to rotate contra-clockwise by spring 2 which was only partially distended during the closing movement of said principal contacts. However the principal movable contact does not immediately start its movement as the roller 5 passes along the cam groove 3b from which it is not yet freed. During this time the air at the left of piston 1 is pushed back through a hollow insulator 29 which supports a part of the circuit-breaker and into a chamber 30 in which is located the principal fixed contact 8, so as not to effect the separation of said two principal contacts until the air pressure for blowing the arc has reached its most efficient value. As the roller 5 leaves said cam groove 3b thus liberating said lever 6 the latter swings contra-clockwise under the action of spring 31, and thus separates said principal contacts 7 and 8, and the principal arc 9 is blown by the compressed air which continues to blow through said chamber 30, driven by the piston 1 which reaches the end of its stroke under the action of spring 2.

In accordance with the invention supple- 75

mentary energy for the blast is borrowed from the auxiliary arc. To this end contacts 10 and 11 are located within a chamber 31 preferably separated from the chamber 30 containing the principal fixed contact as above set forth. The gases generated by said auxiliary arc 12 as well as the air within said chamber 31 the pressure of which is increased to a very high degree by the heat generated by said auxiliary arc, are blown against the principal arc 9, either directly or after contacting with a flame shield 32 by which they are cooled, the blast thus furnished being of an intensity proportionate to the intensity of the current to be interrupted.

- 15 In accordance with the invention also said auxiliary arc 12 forms before the principal arc when the intensity of the current to be interrupted exceeds a certain intensity value. To this end means are provided herein comprising 20 a relay 16 which operates instantaneously but only when said intensity value is exceeded, the coil 28 for separating the contacts being supplied with current by a relay 33 the operation of which is retarded.
- 25 When the intensity of the overcharge current to be interrupted is inferior to said intensity value above referred to, the relay 33 alone operates and said coil 28 causes separation of the arc drawing contact as above set forth. On 30 the other hand when the intensity of the current to be interrupted exceeds said intensity value, said relay 16 operates immediately to free said lever 13 which under the action of said spring 14 separates said auxiliary contacts.
- 35 Furthermore said lever 13 in turning about its fulcrum acts upon the lever 26 to cause the latter also to turn and move the core of said coil 28 through a suitable link connection 34. The lever 27 is thus freed and the principal contacts 7, 8 40 start to separate but only when said roller 5 has escaped from said cam groove 3b, that is to say after a certain time has elapsed and after separation of contacts 10 and 11.

To the blast produced by said auxiliary arc 12 there is therefore added that produced by piston 1. To facilitate this the currents of compressed air produced by said arc 12 and said piston are directed against the arc 9 along parallel courses. As shown in Fig. 1, said two air currents are concentric.

Said two compressed air currents act simultaneously and thus combine their blowing action. The blast from piston 1 continues after extinction of the arcs 9 and 12, thus scouring the space 55 between and about the principal contacts 7 and 8 and precluding any restriking of the arc.

The invention contemplates the use of any suitable arrangement to produce the concentric flow of said two compressed air currents. In the illustrative embodiment of the invention this result may be obtained by using a principal fixed contact which is hollow and the hollow interior of which communicates with the compressor cylinder as shown in Fig. 2. This figure is a longitudinal section of that part of the circuit-breaker containing the principal fixed contact and the two auxiliary contacts the remainder of said circuit-breaker having the same arrangement as that shown in Fig. 1. Referring to Fig. 1 a channel 35 leads from an insulator 29 and conducts the air propelled by piston 1 into the interior space 36 of said main fixed contact 8.

The interior chamber of the hollow fixed principal contact may communicate with the chamber in which the auxiliary arc is formed. Such

an arrangement is shown in Fig. 3. As in the case of Fig. 2 so also in the case of Fig. 3, only that part of the circuit-breaker containing the principal fixed contact and said auxiliary contact is illustrated, the remainder of said circuit-breaker being of the same construction as that shown in Fig. 1. The principal and auxiliary contacts as well as the arcs struck thereby are indicated in said Figs. 2 and 3 by the same reference characters as in Fig. 1. In Fig. 3, the interior chamber of the hollow fixed contact 8 communicates with the chamber 31 in which the auxiliary arc is struck and the concentric chamber 38 of said hollow contact communicates with the air compressor which is diagrammatically indicated by said piston 39.

In accordance with the invention a certain degree of simultaneous action of the two compressed air currents referred to may be obtained by directing said currents in opposite directions against said arc 9 as shown illustratively in Fig. 4. In the illustrative embodiment shown in said figure the operation of the main and auxiliary contacts and the generation of the air blast may be and, as is herein shown, are identical with those illustrated in Fig. 1. The corresponding means have been omitted from Fig. 4 in order not unnecessarily to complicate the drawings, only the piston 1, the driving spring 2, the lever 5 for operating the principal movable contact 7, that part of the circuit-breaker containing the principal fixed contact 8 and the auxiliary contacts, as well as the particular means and features to be considered have been shown diagrammatically in order that the invention may be clearly understood. The compressed air heated by the auxiliary arc is conducted to the fixed contact 8, while the air driven by the piston 1 is conducted through said hollow insulator 29 into a cylinder 40 in which said movable contact 7 operates. The gases and the compressed air produced by the arc 12 are directed against that point of attachment of the arc 9 which is within the chamber 41 while the blast of compressed air from the piston 1 is conducted through openings or ports provided in a partition 42 and into a pipe 43 surrounding the movable contact, whence it is directed against the other point of attachment of said arc 9.

The energy for the blast generated by said auxiliary arc and that produced by the compressor may act successively. In that case the blast generated by said auxiliary arc, which always preponderates, starts first and operates alone. The blast from the compressor starts to operate later and adds its operation to that generated by said arc; it scours the space separating and surrounding the contacts and completes the blowing of the arc, thus precluding any restriking of the latter.

Any one of the forms of circuit-breakers above described may be provided with a resistance serving to delay the re-establishment of the tension. Said resistance may be applied either mechanically or pneumatically and will preferably shunt the auxiliary arc and, the case arising, the principal arc. When the intensity of the current (short circuit) to be cut is weak, the interruption of said current is effected without the insertion of said resistance by using only the blast produced by the compressor. When however said intensity becomes considerable the arc of the auxiliary contacts produces a blast and inserts or throws said resistance 81 into operation. The current which remains for the principal contact to cut is therefore only

a current the intensity of which has been reduced by said resistance.

A capacity may be substituted for said resistance in all the circuit-breakers of the latter type and said capacity may be rendered operative either mechanically or pneumatically and will preferably shunt the auxiliary arc and the case arising the principal arc.

The compressed air blast produced by the compressor cylinder may not only act simultaneously with that supplied from the chamber in which the auxiliary arc is struck but may also act after the arc has been extinguished. This has the advantage that the space about the contacts is efficiently and thoroughly scoured, any restriking of the arc being thus precluded. This operation takes place automatically in the majority of the apparatus above described, by causing the principal contacts and the auxiliary contacts to move at a suitable regulated speed and by making the compressor plant of suitable dimensions.

Among the many advantages possessed by apparatus embodying the present invention may be mentioned the increase in the rupturing power of the usual circuit breakers which themselves compress the air required for blowing their arcs, as well as the possibility of regulating the intensity of the arc-extinguishing blast proportionally to the intensity of the current to be cut, and the fact that small arcs can be extinguished as well as larger arcs.

I am aware that the present invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

I claim:

1. Electric circuit breaker with compressed fluid blow out, comprising, in combination, relatively movable main arc-drawing contacts; relatively movable auxiliary arc-drawing contacts 45 mounted in series with said main arc-drawing contacts; a chamber for said main arc-drawing contacts; a separate chamber for said auxiliary arc-drawing contacts; mechanism for opening and for closing said main arc-drawing contacts; mechanism for opening and for closing said auxiliary arc-drawing contacts; fluid compressing mechanism operatively connected to the arc-drawing contact closing mechanism; means for rendering said auxiliary arc-drawing contact opening mechanism 55 operative to open said contacts only when and after the current to be cut reaches a certain intensity, and before the main contacts are opened; means to direct a blast of compressed fluid against the main arc from said fluid compressing mechanism; and means to direct a blast of compressed fluid against said main arc from the chamber of said auxiliary arc.

2. Electric circuit breaker with compressed fluid blow out, comprising, in combination, relatively movable main arc-drawing contacts; relatively movable auxiliary arc-drawing contacts mounted in series with said main arc-drawing contacts; a chamber for said main arc-drawing contacts; a separate chamber for said auxiliary arc-drawing contacts; mechanism for opening and for closing said main arc-drawing contacts; mechanism for opening and for closing said auxiliary arc-drawing contacts; fluid compressing mechanism, including a piston operatively connected to the arc-drawing contact closing mechanism;

means for rendering said auxiliary arc-drawing contact opening mechanism operative to open said auxiliary contacts only when and after the current to be cut reaches a certain intensity, and before the main contacts are opened; means to direct a blast of compressed fluid against the main arc from said fluid compressing mechanism; and means to direct a blast of compressed fluid against said main arc from the chamber of said auxiliary arc.

3. Electric circuit breaker with compressed fluid blow out, comprising, in combination, a fixed main arc-drawing contact; a chamber containing said contact; an inclosure for said chamber, terminating in an exhaust mouth-piece for the compressed fluid blast; a movable main arc-drawing contact adapted to be withdrawn outwardly from said chamber and said inclosure to draw an arc; relatively movable auxiliary arc-drawing contacts mounted in series with said main arc-drawing contacts in a second chamber near that containing said fixed main arc-drawing contact; mechanism for opening and for closing said main arc-drawing contacts; mechanism for opening and for closing said auxiliary arc-drawing contacts; a cylinder provided with a piston to provide compressed fluid within the circuit breaker, said piston being operatively connected to said arc-drawing contact closing mechanism; means for rendering said auxiliary arc-drawing contact opening mechanism operative to open said auxiliary contacts only when and after the current to be cut reaches a certain intensity, and before the main contacts are opened; means for conveying compressed fluid from said cylinder into said chamber containing said fixed main arc-drawing contact; and means for conveying compressed fluid from said chamber containing said auxiliary arc-drawing contacts between said chamber containing said fixed main contact and said exhaust mouth-piece.

4. Electric circuit breaker with compressed fluid blow out, comprising, in combination, a fixed main arc-drawing contact; a chamber adapted to contain said contact and terminating in an exhaust mouth-piece for the compressed fluid blast; a movable main arc-drawing contact adapted to be withdrawn outwardly from said mouth-piece; a tube mounted opposite said mouth-piece and in alignment therewith to receive said movable contact when it is withdrawn from said mouth-piece; relatively movable aux-

iliary arc-drawing contacts mounted in series with said main arc-drawing contacts, in a chamber near that containing said fixed main arc-drawing contact; mechanism for opening and for closing said main arc-drawing contacts; mechanism for closing said auxiliary arc-drawing contacts; a cylinder containing a piston to furnish compressed fluid in the circuit breaker, said piston being operatively connected to the arc-drawing contact closing mechanism; means adapted to open said auxiliary arc-drawing contacts only when and after the current to be cut reaches a certain intensity and before the main contacts are opened; means to convey the fluid compressed by said auxiliary arc into said mouth-piece, and means to convey fluid compressed by said cylinder into said tube, the main arc thus receiving a blast of compressed fluid from said mouth-piece and a blast of compressed fluid from said tube.

5. Electric circuit breaker with compressed fluid blow out, comprising, in combination, relatively movable main arc-drawing contacts; a chamber containing said contacts; auxiliary arc-drawing contacts mounted in a chamber separate from that containing said main arc-drawing contacts and in series with the latter; mechanism for closing said main arc-drawing contacts and said auxiliary arc-drawing contacts, the mechanism for closing said main arc-drawing contacts including a cam for closing the latter; mechanism for opening said main arc-drawing contacts and for opening said auxiliary arc-drawing contacts; a cylinder and piston to provide compressed fluid in the circuit breaker, said piston being operatively connected to the arc-drawing contact closing mechanism, the piston rod being connected to the mechanism for closing said auxiliary arc-drawing contacts; an electric relay to render said auxiliary arc-drawing contact opening mechanism operative to open said auxiliary contacts only when and after the current to be cut reaches a certain intensity and before said main arc-drawing contacts are opened; means to direct a blast of compressed fluid against the main arc from said cylinder; and means to direct a blast of compressed fluid against the main arc from said chamber of said auxiliary arc.

BERNARD MARIE HILAIRE
